(57) **CLAIM**

I claim the ornamental design for a lock assembly component, as shown and described.

DESCRIPTION

FIG. 1 is a perspective view of a lock assembly component according to a first preferred embodiment of my new design; FIG. 2 is a second perspective view of the lock assembly component of FIG. 1; FIG. 3 is a left side elevational view of the lock assembly component of FIG. 1, the right side elevational view being the same;

FIG. 4 is a front elevational view of the lock assembly component of FIG. 1, the rear elevational view being the same; FIG. 5 is a top plan view of the lock assembly component of FIG. 1; FIG. 6 is a bottom plan view of the lock assembly component of FIG. 1;

FIG. 7 is a perspective view of a lock assembly component according to a second preferred embodiment of my new design; FIG. 8 is a second perspective view of the lock assembly component of FIG. 7; FIG. 9 is a third perspective view of the lock assembly component of FIG. 7; FIG. 10 is a right side elevational view of the lock assembly component of FIG. 7, the left side elevational view being the same; FIG. 11 is a top plan view of the lock assembly component of FIG. 7;

FIG. 12 is a front elevational view of the lock assembly component of FIG. 7, the rear elevational view being a mirror image thereof; and, FIG. 13 is a bottom plan view of the lock assembly component of FIG. 7.

The broken lines in FIGS. 1, 7, and 8 represent environment and are for illustrative purposes only and do not constitute part of the claimed design.

1 Claim, 5 Drawing Sheets
